Primary Examiner — Marianne Pandozzi

(74) Attorney, Agent, or Firm — Carl M. Napolitano;
GrayRobinson, P.A.(57) **CLAIM**

The ornamental design for a color blocking tape unit, as shown and described.

DESCRIPTION

FIG. 1 is a front elevation view of a color blocking tape unit; FIG. 2 is a rear elevation view thereof;

FIG. 3 is a right side view thereof;

FIG. 4 is a left side view thereof;

FIG. 5 is a top plan view thereof;

FIG. 6 is a bottom plan view thereof;

FIG. 7 is an in use perspective view thereof;

FIG. 8 is an in use perspective view thereof;

FIG. 9 is an in use perspective view thereof; and,

FIG. 10 is an environmental perspective view thereof shown on a dispenser.

The broken lines in the drawings are included for the purpose of illustration and form no part of the claimed design.

1 Claim, 4 Drawing Sheets(56)
